UNITED STATES PATENT OFFICE.

ZENAS P. CANDEE AND JAMES H. OLCOTT, OF WATERBURY, CONNECTICUT, ASSIGNEES
TO THE WATERBURY FARREL FOUNDRY AND MACHINE COMPANY, OF WATER-
BURY, CONNECTICUT, A CORPORATION OF CONNECTICUT.

ASSEMBLING MACHINE.

Application filed March 8, 1920. Serial No. 334,262.

To all whom it may concern:

Be it known that we, ZENAS P. CANDEE and JAMES H. OLCOTT, citizens of the United States, residing at Waterbury, in the county 5 of New Haven and State of Connecticut, have invented certain new and useful Improvements in Assembling Machines, of which the following is a specification, reference being had therein to the accompanying 10 drawings.

Our invention relates to new and useful improvements in assembling machines and for the purpose of illustration is shown and described herein for the assembly of the 15 disks and the caps of collapsible tubes, which heretofore has been done by manual means. While thus specifically applied, it is not, however, limited to such use. It is the object of this invention, among other things, 20 to provide a mechanism that will perform the functions above indicated with elements so designed and operated as to insure certainty of action, eliminate the possibility of error in assembling, which will be entirely 25 automatic and produce results that throughout its series of operations will be entirely uniform, to safe-guard the operations so that the possibility of damage or injury either to the machine or parts being 30 assembled is reduced to the absolute minimum and to accomplish these and other results with mechanism of the fewest possible parts so designed as to be economically constructed and readily assembled.

To these, and other ends, our invention 35 consists in the assembling machine, having certain details of construction and combinations of parts, as will be hereinafter described and more particularly pointed out in 40 the claims.

Referring to the drawings, in which like numerals of reference designate like parts in the several figures;

Figure 1 is a plan view of our invention; 45 Figure 2 is an enlarged fragmentary view of the transfer mechanisms and adjacent parts;

Figure 3 is an enlarged sectional view thereof taken upon line 3—3 of Figure 2; 50 Figure 4 is a detail plan view of the indexing mechanism;

Figure 5 is an enlarged sectional view taken substantially upon line 5—5 of Figure 1;

Figure 6 is an enlarged sectional view of 55 the head mechanism and the parts adjacent thereto showing the head in a position 90° from that illustrated in Figure 5;

Figure 7 is a fragmentary detail view of 60 a portion of the transfer mechanism;

Figure 8 is an end view of the punch and adjacent mechanism.

In the embodiment of the machine herein disclosed, the disks, usually of cork are delivered by feed mechanism to one station 65 and the caps to a second station, and from these stations are independently conveyed to receiving stations. A reciprocating intermittent rotary head is operative near these stations and is provided with means 70 for picking up a disk at its delivery station lifting it therefrom and carrying it through a rotary path and inserting it in the cap at its delivery station, and then lifting the parts thus assembled, that is, the disk and 75 cap, and carries them through a rotary path to a point where the assembled cap and cork are released and drop through a chute to a place conveniently arranged to receive them. 80

In the practice of our invention we provide a body member having an upper table 10 and a lower table 11, preferably joined by tie bars 12, in which is journaled a shaft 13 having a driving wheel 14 thereon and a 85 cone pulley 15, which is utilized for connection by belt (not shown) with a similar cone pulley 16, through which a feed dial 17 is rotated.

Rotatably mounted upon a fixed bracket 90 18 is a drum 19, from which extends a guideway 20 and near the periphery of the dial is another guideway 21. The parts just described are elements of the feed mechanism whereby the disks are delivered from the 95 drum 19 through the guideway 20 to the station 22 and the caps are delivered through the guideway 21 to the station 23. This feed mechanism is only illustrated as one general form of means for delivering the caps and 100 disks to the stations 22 and 23 and any other feed device that will perform the same function is equally adapted for use with our invention, the requirement being that a continuous supply of disks and caps shall be 105 delivered to these stations in their proper relative positions.

Secured to the top of the upper table 10

is a plate 24, within which are slidably mounted the transfer fingers 25—26, the former being for use in connection with the disks and the latter with the caps. Fixed in 5 the plate 24 adjacent to the said fingers are the stop plates 27 and 28, each of these having a shoulder 29 thereon which is engaged by the shoulder 30 upon the fingers 25—26 to limit the outward position thereof. The in- 10 ward position of these fingers is adjustably limited by the stop screws 111. In the outward positions of the fingers the notches 31—32 therein register with the stations 22 and 23 respectively, that portion of the fin- 15 gers between said notches and the outer end thereof being of such length that no disk or cap can arrive at said stations except when the notches 31 and 32 are in register therewith. After the assembling of the fingers 20 and stop plates in the plate 24, the same are held therein against disengagement therefrom by a cover plate 33. A reciprocatory movement is imparted to the fingers 25 and 26 from the shaft 13 through the cam 34; 25 yoke 35 having a cam roll 36 thereon that engages the periphery of said cam; a rock shaft 37 journaled in the brackets 38 secured to the table 10 and connected by the tie bar 39; a rock arm 40 fixed to the rock shaft 37 30 and connected to the yoke 35 through the rod 41, said rod being threaded at one end into said yoke 35 and at the other end in a block 42 pivotally connected to the rock arm 40, nuts 43 threaded onto said rod providing 35 means for locking said rod against accidental rotation and also relative adjustment between the parts; and arms 44 and 45 connected with the rock shaft 37 having rounded outer ends 46 which engage the slide 40 blocks 47 secured to the fingers 25 and 26. Rotation of the cam 34 imparts a rocking movement to the shaft 37 and through the arms 44 and 45 this motion becomes a reciprocating motion in the fingers 25 and 26, the 45 extent of the reciprocation, its timing and the dwell of the fingers at the stations being determined by the shape of the cam 34. A spring 107 maintains the contact of the roll 36 with the cam 34. The arm 45 is supplied 50 at one end with a bolt 48 therethrough with a nut 49 thereon so as to permit of radial adjustment of said arm about the rock shaft 37, while the arm 44 is fixed to the said shaft. It is only necessary for purposes of 55 adjustment that one arm should be adjustable on the shaft although within our invention both arms may be provided with adjusting means if desired.

Journaled in the upper table 10 and in a bearing 50 connected with the lower table 11, is the shaft 51. Near the upper end of the said shaft is a bushing 52 having connection by means of a key 54 with said shaft so as to prevent its rotation thereon, but permitting 60 a parallel movement thereon, and upon which bushing is mounted the cam plate 53, a nut 55 threaded on said bushing in co-operation with the head of the said bushing preventing endwise movement of the cam plate in connection therewith, the relative 70 position of this bushing being determined and fixed by the nuts 56 and 57. Rotation of cam plate is prevented by the uprights 112 secured to a fixed part. Secured to the top of the cam plate 53 is an arm 58, 75 through which is threaded a stop screw 59 the end of which engages the top of the tie bar 39 when the cam plate is in its down position. By this mechanism the down position of said cam plate and the adjacent parts 80 is adjustably determined with great exactness and nicely.

In the said shaft 51, substantially diametrically opposite each other and projecting radially therefrom, are the registering keys 85 60, and mounted on the shaft 51 with the upper ends 61 of said registering keys 60, projecting into the guideways provided thereon, is the punch holder 62, which is held against endwise movement on said shaft by the nut 63 threaded thereon and the registering keys 60, (see Figures 5 and 6). The punch holder 62 is provided in its periphery with two notches 64, which register with the index finger 65 fixed in the tie 95 bar 39 when the punches are in register with the delivery stations.

Mounted in the punch holder 62, diametrically opposite each other, are the punches 67, held against movement by screws 68. 100

The head 69 of the punch is of substantially the same or less diameter than that of the disks and the body portion is provided with a chamber 70, within which is movably mounted the needle holder 71, having a head 72 on one end and an annular groove 73 near its opposite end. The needles 74 are each provided with a head 75 which project into the groove 73 (see Figure 6), the top of the needle being held against the shoulder at 105 one end of said groove and the lower portion of said head engaging the shoulder at the opposite end of said groove, thereby preventing endwise movement of the needle in relation to the needle holder 71 but moving therewith. The pointed ends of the needles project through openings 76 in the periphery of the punch head 69. 110

That portion of the end of the head 69 of the punch is cut away surrounding the needles 74, as shown at 77, in Figure 8. It has been found desirable in some classes of work to have an open space surrounding the needle at the end of the punch, and for this purpose a recess 77 is provided but obviously 115 may be omitted if desired.

In the drawings we have shown three needles grouped around the punch, but more or less may be used if desired.

Surrounding the needle holder 71 and con- 120 125

tacting with the punch head 72 is a washer 78 against which rests one end of a coil spring 79, which surrounds each of the punches 67 and abuts at its opposite end 5 against the punch holder 62. The top of the head 72 during its rotation about the axis of the shaft 51 rides against the underside of the cam plate 53, at which time the points of the needles are projecting below the end 10 of the punch head 69. At one point, however, in the path of the head 72, a recess 82 is provided in the underside of the cam plate 53 so that when the said head registers therewith the spring 79 moves the needle holder 71 upwardly, thereby withdrawing the pointed ends of the needles within the end of the punch 69 and the disk or any other article thereon is released.

During the endwise movement of the 20 shaft 51 the same is rotated through an arc of 180°. The mechanism whereby this is accomplished consists of a sleeve or barrel cam 83, a second sleeve or barrel cam 84, a lever 85 having a fulcrum pin 86 therein 25 which lies within the slot 87 in the bracket 88 fixed to the upper table 10, an eccentric 89 fixed on the shaft 13, an eccentric strap 90 surrounding the eccentric 89 and pivotally connected with the lever 85 by the 30 pintle 91. The forked end of the lever 85 is provided with shoes 92, which project into the groove 93 in the cam 83. A coil spring 94 surrounds the shank of the cam 84, one end thereof being fixed in said cam 35 and the other end in the collar 95 fixed to the shaft 51, as shown in Figure 5.

Secured to the lower table 11 is a standard 40 96, in which is fixed a stud 97 having a conical roll 98 at its outer end which lies between the cam faces of the cams 83 and 84. As the shaft 51 is moved vertically through the eccentric 89 and cam lever 85 the roll 98 on the fixed stud 97 rotates said shaft 180°, the cam being shaped to produce this result. This rotation of the shaft 45 is accomplished at each endwise movement of the shaft 51, so that upon the completion of the full movement of the said shaft between the limit of its endwise movement, the shaft 51 and punch holder connected therewith are rotated through a complete 50 circle, the grooves in said cam being so formed that a portion of the movement of the shaft near the ends of its stroke is a 55 straight, parallel movement without rotation. The mechanisms for moving this shaft endwise and rotating it at one and the same time are made the subject matter of another application, and therefore is not 60 herein described more in detail. In operations, the fingers 25 and 26 during their reciprocation move respectively from the stations 22 and 23 a disk and a cap, carrying the same to the delivery stations 99 and 65 100, at which time they are in line with the punches 67. At this point the fingers being held against movement, the shaft 51 is moved downwardly and the points of one of the groups of needles 74 enter and spear the disk at station 99. The shaft 51 is now 70 moved upwardly and with it the disk is carried by the needles and the punch. At the same time the punch holder is rotated through an arc of 180°, bringing the speared disk into line with the station 100, which 75 now holds a cap. The next downward movement of the shaft 51 causes the disk upon the end of the needles to enter the cap and be assembled therewith at station 100 and the needles in the other punch, now 80 in register with the station 99 engage a new disk. The shaft 51 is again moved upwardly at which time the assembled disk and cap at station 100 move upwardly and the disk at station 99 travels with the respective 85 punches. After moving in a straight path for a limited distance the punch holder is rotated through an arc of 180°, during which time the head 72 of the plunger carrying the assembled disk and cap enters the 90 detent 82 in the cam plate 53, withdrawing the needles from the disk, and the assembled cap and disk now being released, drop through the funnel 101 into the discharge tube 102, where the assembled articles are conveyed to a receptacle 95 conveniently arranged to receive them.

With the next downward movement of the shaft 51 the needles last stripped from the assembled articles pick up a new disk 100 and the old needles having a disk thereon assemble the same with a cap and the operations above described are repeated. During this downward movement the key 60 adjacent to the station 100 passes in front 105 of the notch 81 in the finger 26 if the fingers 25 and 26 are in the proper relative positions, that is, with notches 22 and 23 in register with the stations 99 and 100. If, however, the fingers are not in such position 110 the bottom of the last mentioned key 60 engages the top of the finger 26 and prevents further downward movement thereof, and the shaft 51 with which it is connected. This prevents downward movement of the 115 cam 83 and the fulcrum of the lever 85 is shifted from the fulcrum point 86 to the axis of the shoes 92, the pin 86 during this motion riding through the slot 87 against the tension of the spring 105 which returns 120 the pin 86 to its former position, when normal conditions are assumed. This safety device for the fingers 25 and 26 is desirable, as their action in one direction is in part dependent upon the spring 107. When in 125 proper register with each other the notch 64 engages the index finger 65, but if not in such register the underside of the punch holder 62 engages the top of the index finger and the shaft 51 held against move- 130

ment, this being permitted through the shifting of the fulcrum of the lever 85 as above described.

The disks and caps are moved to the stations 99 and 100 in substantially the same plane, this latter being the top surface of the block 106. As the disk is speared at station 99 and carried to station 100, the disk at this latter station must be in the same plane as at the former, disregarding the thickness of the cap. Hence a movable platform is provided at station 100, which yields as the disk upon the punch, in register with said station, engages the cap and continues to yield until the disk thereat is in the same plane as the disk at station 99, now being speared preliminary to its transfer. This yielding mechanism comprises a block 106, pivotally mounted lever 103, spring 104 and adjustable stops 80. The up position of this block is maintained by the spring 104 and varied as well as limited by the stops 80.

During the movement of the punch holders up and down the fingers 25 and 26 are operated so as to always present at delivery stations 99 and 100 a disk and cap respectively, but no more than one cap or cork can be delivered at each of these stations at one and the same time, as the ends of the fingers 25—26 always cover the receiving stations 22 and 23 and prevent the entrance of another article therefrom except when the notches 31 and 32 register therewith. If for any reason the disk or cap is not lifted out of the receiving fingers at the delivery stations by the movement of the punches, then the disk or cap, or both move back with said fingers to the stations 22 and 23, and at the next movement of the fingers 25 and 26 are returned to the stations 99 and 100.

To readily assemble or take out the punches 67 and its associated mechanism, without disturbing the cam plate 53, we have provided an opening 108 through said cam plate and inserted therein a removable plug 109 which is held in position by one or more screws 110, with the bottom face of said plug flush with the lower face of said cam plate. By removal of this plug the punch 67 or adjacent parts may be easily placed in position or removed therefrom with the minimum inconvenience. While we have only illustrated one plug 109, another can be added within our invention, diametrically opposite to the one shown. By the use of two plugs the necessity of rotating the shaft 51 to successively bring the punches into register with the plug 109 is obviated.

Within the scope of the appended claims, changes and alterations may be made in our invention, aside from those herein suggested, and we would therefore have it understood that we do not limit ourselves to the exact construction herein shown and described, but

claim all that falls fairly within the spirit and scope of the appended claims.

Having described our invention, what we claim as new and desire to secure by Letters Patent is:

1. Mechanism for automatically holding a tube cap in one position, independent mechanism for taking a disk from another position and placing it within said tube cap while so held, which latter mechanism in part enters said disk, and means for actuating said latter mechanism whereby both said disk and tube cap when so assembled will move as a unit. 70

2. In mechanism of the character described, the combination with means for delivering a disk at one station, and a cap at another station, of means, that in part enters said disk, for taking said disk from one of said stations and transferring it to and assembling it with the cap located at its station. 85

3. In a device of the character described, mechanism for taking an article from a station, which in part enters said article, and transferring it to another station and there assembling it with a second article, then taking away from said latter station the articles so assembled; and means for discharging said articles from said mechanism at a delivery point, the aforesaid mechanism having constant engagement with the first of said articles from the first mentioned station until discharged at the delivery point. 90

4. In a device of the character described, 100 wherein two articles are assembled; mechanism for taking one article from a station, which in part enters said article; conveying said article to a second station and placing it into a second article located at said latter 105 station, the relative construction and operation of said mechanism being such that both said articles so assembled will be withdrawn from the second station as a unit; and means for subsequently stripping said assembled 110 articles from said taking and conveying means.

5. In a device of the character described, mechanism for taking an article from a station, that in part enters said article, and transferring it to another station; means for so controlling the movement thereof that at said latter station it will be assembled with another article and withdrawn when both of said articles are so assembled thereby; and means for actuating said mechanism whereby said assembled article will be conveyed to a delivery point between said stations, said mechanism having a reciprocatory and a rotary movement relatively to said stations. 115

6. In a device of the character described, wherein a disk and a tube cap are assembled, the combination with mechanism for presenting a disk at one station; of means for presenting a cap at a second station; means 120

that in part enters said disk for taking said disk from its station and placing it within said cap at its station, where it is held therein by frictional engagement therewith; and 5 means for actuating said taking and placing means whereby both said disk and cap so assembled will be withdrawn from said second station and moved to a delivery station.

7. In mechanism of the character described, the combination with means for delivering at separate stations two or more articles; movable members operative in line with each of said stations; means for actuating said movable members whereby they 10 may be brought successively into register with each of said stations; of holding means connected with said movable members that in part enters an article at one of said stations and during the movement of said 15 movable members conveys one of said articles from one station to another of said stations; and means for actuating the holding means connected with said movable members while traveling between said stations whereby an 20 article thereon may be stripped therefrom.

8. In mechanism for assembling a tube cap and a disk, comprising elements which deliver said cap and disk at different stations; a member for taking a disk from one 30 of said stations, arranged so as to in part enter said disk, take only one disk at a time, and transfer it to and assemble it with a cap at another of said stations, conveying the assembled disk and cap from said latter station to a discharge point; and means for releasing said assembled disk and cap from 35 said member at said discharge point.

9. In mechanism of the character described, the combination with means for taking 40 out of a station an article placed therein, said means in part entering said article; means for moving the same to another station and inserting said article into another article at said latter station; and means for 45 holding said latter article so that it may yield during the assembling operation.

10. In combination with a carrier member; of a punch mounted therein; a holder within said punch; a needle connected with 50 said holder so as to move therewith and in one of its positions project beyond the end thereof; means for moving said holder within said punch; and means for moving said carrier member in a path at substantially a 55 right angle to the movement of said needle within said holder and while the end thereof projects beyond the end of the holder.

11. In a device of the character described, wherein a pierceable disk is assembled with 60 a cap, the combination with means for delivering a disk to one station and a cap at another station; a movably mounted element engaging said disk at its station by piercing the same and taking it out of said station; 65 means for causing said element to travel to

a point in register with the cap at its station, then projecting said disk into said tube cap where it is there held by frictional engagement and again moving said element, and with it said assembled disk and cap, and 70 causing it to travel to a point in register with the first mentioned station; and means for releasing the hold of said element on said disk while said latter element is moving between the two stations. 75

12. In mechanism of the character described, the combination with means for taking out of a station an article placed therein that in part enters said article, and then moving the same to another station and by 80 the use of said moving means inserting it in an article at said latter station; of means for automatically limiting the action of said moving means when either the parts of said mechanism or the article are not in their 85 predetermined position.

13. In mechanism of the character described, the combination with means for taking out of a station an article placed therein and then moving the same to another station 90 and by the use of said taking out and moving means inserting it in an article at said latter station; of means for automatically limiting the action of said moving means when the relative position and number of 95 said articles is not as predetermined.

14. In mechanism of the character described, the combination with means for taking out of a station an article placed therein, said means comprising a movable element 100 having holding parts connected therewith that engage said article within the outer edges thereof, and in part enter said article; and means for mounting the same in a carrier member; means for actuating said latter 105 member so that it will take said article from said station and place it in line with another article at a different station, and then actuating said movable element so as to assemble the first mentioned article with the article at 110 the latter station and then withdrawing said movable element at said latter station and again moving it into register with the first mentioned station.

15. In mechanism of the character described, the combination with means for taking out of a station an article placed therein, said means comprising a movable element having holding parts connected therewith that engage said article within the outer 115 edges thereof; means for mounting the same in a carrier member; means for actuating said latter member so that it will take said article from said station and place it in line with another article at a different station, 120 and then actuating said movable element so as to assemble the first mentioned article with the article at the latter station and then withdrawing said movable element at said latter station and again moving it into regis- 125 130

ter with the first mentioned station; and means for actuating the holding parts connected with said movable element while traveling from said second station to said first station as to release therefrom the assembled articles.

16. In combination with a carrier member; of a punch mounted therein; a holder within said punch, having axial grooves therein; a needle in each of said grooves, held against lateral displacement and mounted so as to move therein in a path substantially parallel to their length, said needles in one of their positions projecting beyond the end of said holder; and means for moving said holder in a path at substantially a right angle to the movement of said needles within said holder while the ends project beyond the end of the holder.

17. The combination with means for delivering articles at two or more stations; of a carrier member; means for imparting a rotary and reciprocating movement to said carrier member; and means, independently movable in said carrier member, which when brought into engagement with the article at one of said stations will take the same therefrom and when in register with another of said stations will insert said article in the article at said second station.

18. In a mechanism of the character described having a plurality of delivery stations, the combination with a carrier member; of means for imparting an intermittent rotary movement thereto; means for imparting a reciprocating movement thereto between said intermittent rotary movement; punches connected with said carrier member corresponding in number with said stations; means connected with each of said punches for engaging one of the articles at one of said stations in such manner as to carry the same therewith after engaging it; and means for independently actuating said punch in relation to its adjacent parts so as to cause said punch to release its hold upon said article during the movement thereof.

19. Mechanism for assembling a tube cap and a disk, comprising elements which deliver said cap and disk at different stations; a member having a projecting point; means for actuating said member so that said projecting point will enter said disk at its station, take the same therefrom and carry it to the station where the said cap is located, placing said disk in said cap, thereby assembling it therewith, and taking said assembled cap and disk from said latter station as a unit; and means for releasing said disk from said projecting point, to discharge the assembled cap and disk therefrom.

20. Mechanism for assembling a tube cap and a disk, comprising elements which de-

liver said cap and disk at different stations; a member having a projecting point; means for actuating said member so that said projecting point will enter said disk at its station, take the same therefrom and carry it to the station where the said cap is located, placing said disk in said cap, thereby assembling it therewith, and taking said assembled cap and disk from said latter station as a unit; and means for withdrawing said projecting point from said disk, thereby releasing said assembled cap and disk.

21. Mechanism for assembling a tube cap and a disk, comprising elements which deliver said cap and disk at different stations; a member having a projecting point; means for actuating said member so that said projecting point will enter said disk at its station, and the disk will engage a contact face, take the same therefrom and carry it to where the said cap is located, placing said disk in said cap, thereby assembling it therewith, and taking said assembled cap and disk from said latter station as a unit; and means for releasing said disk from said projecting point, to discharge the assembled cap and disk therefrom.

22. Mechanism for assembling a tube cap and a disk comprising elements which deliver said cap and disk at different stations; a member having a projecting point; means for actuating said member so that said projecting point will enter said disk at its station, and the disk will engage a contact face, take the same therefrom and carry it to where the said cap is located, placing said disk in said cap, thereby assembling it therewith, and taking said assembled cap and disk from said latter station as a unit; and means for releasing said disk from said projecting point, to discharge the assembled cap and disk therefrom, that portion of said contact face adjacent to the projecting point being open.

23. Mechanism for assembling a tube cap and a disk, comprising elements which deliver said cap and disk at different stations; a member having a projecting point; means for actuating said member so that said projecting point will enter said disk at its station, take the same therefrom and carry it to the station where the said cap is located, placing said disk in said cap, thereby assembling it therewith, and taking said assembled cap and disk from said latter station as a unit; and means for withdrawing said projecting point from said disk, thereby releasing said assembled cap and disk, the said withdrawing means being yieldingly controlled.

24. In combination with a carrier member of a punch mounted therein; a holder within said punch having a shoulder thereon; a plurality of needles connected with said holder, and each engaging said shoul-

der so as to move therewith; means for moving said holder within said punch; and means for moving said carrier member in a path at substantially a right angle to the 5 movement of said needles within said holder and while the ends project beyond the end of the holder.

25. Mechanism for assembling a tube cap and a disk, comprising elements which deliver said cap and disk at different stations; a member for taking a disk from its station, arranged so as to take only one disk at a time and transferring it to and assembling it with a cap at its station, taking 10 the assembled disk and cap from said latter station to a discharge point; and means for releasing said assembled disk and cap from said member at said discharge point, comprising an element in the path 15 of said member, constructed so as to permit relative movement of parts connected therewith when the same is in register with said discharge point.

26. Mechanism for assembling a tube cap and a disk, comprising elements which deliver said cap and disk at different stations; a member for taking a disk from its station, arranged so as to take only one disk at a time and transferring it to and assembling 20 it with a cap at its station, taking the assembled disk and cap from said latter station, to a discharge point; and means for releasing said assembled disk and cap from said member at said discharge point, said 25 means comprising an element in the path of said member, having a recess therein adjacent to said discharge point, and in the path of said member, parts of which enter said recess and thereby actuate said releasing 30 means.

27. The combination with means for automatically holding a tube cap in one position, of means for taking a disk from another position and placing it within said tube cap 45 while so held; and supporting means for said tube cap that will yield by the application of pressure upon said tube cap.

28. In mechanism of the character described, the combination with means for delivering articles to a plurality of stations, said means permitting the delivery of only one article at a time to each of said stations; of means for taking out an article from one 50 of said stations that in part enters said article and with the same means transferring it to another of said stations and assembling it with an article located at the latter station.

29. In mechanism of the character described, the combination with means for delivering articles at different stations; means for holding one of said articles at one of said stations upon a yielding support and the other of said articles upon a rigid 55 support; means for taking the article from

the station having the rigid support and placing it into the article upon the yielding support.

30. In mechanism of the character described the combination with means for delivering articles at different stations; means for holding one of said articles at one of said stations upon a yielding support and the other of said articles upon a rigid support; means for taking the article from the 70 station having the rigid support and placing it into the article upon the yielding support, said yielding support being associated with a lever; and spring means for actuating said lever in one direction. 80

31. In mechanism of the character described, the combination with means for delivering articles to different stations located upon opposite sides of a common center; a movable member mounted with its axis co- 35 incident with said common center; means for imparting an intermittent rotary and reciprocatory movement to said movable member; and means mounted in said movable member having an independent movement therin for taking one of the articles from its station and transferring it and assembling it with the article at the other station. 90

32. In mechanism of the character described, the combination with means for delivering a plurality of articles to a plurality of stations; of a carrier member; means for imparting an intermittent and reciprocatory movement to said carrier member; a plurality 100 of members connected with said carrier member; means for imparting movement to one of said members independently of the other member, said means comprising a cam plate, engaged by each of said plurality of 105 members; and means for varying the relative position of said cam plate and carrier member.

33. In combination with a holder having a contact face thereon, of a plurality of needles connected with said holder, of means for moving said needles within said holder in a path substantially parallel with the length thereof so that in one position the ends of said needles project beyond said 110 contact face, that portion of said contact face adjacent to the projecting portion of said needles being open. 115

34. In combination with a holder having a contact face thereon, and a plurality of axial grooves therein with that portion of the contact face adjacent to said grooves being recessed; of a needle in each of said grooves; means for holding the same against lateral displacement; and means for actuating said needles within said holder whereby the ends of said needles may in one of their positions project beyond the said contact face. 120

35. In mechanism of the character de- 125

scribed, a carrier member, means for delivering articles to each of a plurality of stations, means connected with said carrier member for taking an article from one of said stations; and means for actuating said carrier member whereby during a single movement thereof an article will be taken from one station and an article taken from the same station at the preceding movement 10 thereof will be assembled with the article at the second station.

36. The combination with the carrier member; of a punch mounted and held against movement therein; a holder within 15 said punch; a plurality of needles connected with said holder, with the ends projecting beyond the end of said punch; and means for actuating said holder whereby the said needles will be withdrawn within the end of 20 said punch.

37. In mechanism of the character described, a carrier member, means for delivering articles to each of a plurality of stations; means connected with said carrier 25 member corresponding in number with said stations for taking an article from one of said stations; and means for actuating said carrier member whereby during a single movement thereof an article will be taken from 30 one station and an article taken from the same station at a preceding movement thereof will be assembled with the article at the second station.

38. In mechanism of the character described, the combination with means for taking out of a station an article placed therein and then moving the same to another station and by the use of said moving means inserting it in an article at said latter 40 station; means, including a fulcrumed member for actuating in part said moving means; and means for mounting said fulcrumed member so that its fulcrum point will shift and limit the movement of said inserting means, if normal conditions do not 45 prevail at said latter station.

39. Mechanism for assembling a tube cap and a disk, comprising elements which deliver said cap and disk at different stations; a member having a group of projecting 50 points; means for actuating said member so that said projecting points will enter said disk at its station, take the same therefrom and carry it to the station where the said cap is located, placing said disk in said cap, 55 thereby assembling it therewith, and taking said assembled cap and disk from said latter station as a unit; and means for releasing said disk from said projecting points, to discharge the assembled cap and disk there- 60 from.

40. In mechanism of the character described, a carrier member, means for delivering articles to each of a plurality of stations, means connected with said carrier 65 member corresponding in number with said stations for taking an article from one of said stations; means for actuating said carrier member whereby during a single movement thereof an article will be taken from 70 one station and an article taken from the same station at a preceding movement thereof will be assembled with the article at the second station; and means for stripping articles from said holding means while mov- 75 ing from one station to another.

41. In mechanism of the character described, the combination with means for taking out of a station an article placed therein and then moving the same to another 80 station and by the use of said moving means inserting it in an article at said latter station; and means for actuating said moving means whereby the extent of the inserting movement will be automatically limited, if 85 an article is not presented at said latter station.

In testimony whereof, we have hereunto affixed our signatures.

ZENAS P. CANDEE.
JAMES H. OLcott.
